UNITED STATES PATENT OFFICE

2,419,446

ELECTRIC CIRCUIT BREAKER

Cedric Harold Flursheim, Bowdon, England, assignor to Metropolitan-Vickers Electrical Company Limited, a British company

Application July 18, 1944, Serial No. 545,440
In Great Britain July 28, 1943

9 Claims. (Cl. 200—148)

1

This invention relates to air or gas blast electric switches or circuit breakers of the kind in which cooperating contacts mounted within a contact or arcing chamber are adapted to be separated by the application of pressure to said chamber which is provided with one or more discharge openings or the equivalent so that said pressure will cause a blast of air or gas past the contacts thereby to extinguish the arc drawn upon interruption of the circuit through said contacts.

In a well-known form of such switches the arcing or contact chamber above referred to comprises a tubular member of insulating material within which the contacts are mounted for relative movement parallel with the axis of said tubular member, the air or gas for producing the blast being caused to flow axially through said tubular member and past a nozzle therein which may be formed by one of the contacts or by a separate member such as of insulating material. Such arrangements, however, suffer from the disadvantage that the contacts and particularly the moving contact displaceable by the pressure within the arcing chamber are not readily accessible.

The present invention has for its object to provide an improved arrangement of arcing or contact chamber and contacts which whilst applicable in a single-break switch is well adapted where desired for application in series with one or more similar units to provide a multibreak switch. The invention also provides according to another aspect, such arrangements whereby improved accessibility of the contacts and particularly of a contact or contacts displaceable by the gas pressure is obtained.

In order that the invention may be more clearly understood reference will now be made by way of example to the accompanying diagrammatic drawings, in which

Fig. 1 is an elevation mainly in section of a preferred contact arrangement according to the invention,

Figs. 2, 3, 4 and 5 show by way of example several applications of the arrangement according to Fig. 1, Fig. 4 being a plan view of the arrangement shown in Fig. 3,

Fig. 6 shows partly in cross-sectional elevation to an enlarged scale an arrangement corresponding with Fig. 5 and incorporating a further feature of the invention,

Fig. 7 is an elevation of a further multi-break switch employing a plurality of contact arrangements according to Fig. 1, and

Fig. 8 is an elevation mainly in cross-section

2

showing a modification of the arrangement of Fig. 1.

Similar parts in the several figures are denoted by like reference numerals.

Referring first to Fig. 1, the contact arrangement is formed as a unit comprising a fixed main contact 1 and a co-operating movable contact 2, mounted within a metal contact chamber 3. The contact 1 comprises a tubular member extending through, and located in a side wall of the chamber 3 by, an insulating bushing 4, which may be of porcelain for example or may be a condenser type bushing. This bushing is retained in place by a ring 4a bolted to a flange on a cylindrical portion 5 of the chamber 3. The contact member 1 is retained in place axially within the bushing by means of a flange 1a and an end plate 1b screwed on to the end of the said member, the flange 1a and plate 1b abutting against the ends of the bushing 4. The moving contact 2, which is also of the tubular form, extends through a cylinder 6 projecting laterally from the side wall of the contact chamber 3 opposite to the bushing 4, said moving contact 2 carrying a piston portion 2a. By means of sliding engagement of the right-hand end of the contact member 2 in a cover plate 7 for the cylinder 6, the contact 2 is guided for longitudinal movement toward and away from the co-operating fixed contact 1, the contacts being shown in the circuit-closed position. The moving contact 2 is connected electrically with the cylinder 6 and thereby with the contact chamber as a whole by means of an annular resilient contact construction 8 with which the contact has sliding engagement. This resilient contact construction may be of any of the well known forms. The contact 2 is biased into engagement with the contact 1 by means of a helical compression spring 9 surrounding the contact 2 and abutting at its ends respectively against the contact construction 8 and the piston 2a.

The contact chamber 3 is in the arrangement shown in Fig. 1 mounted upon a tubular insulator pillar, the upper end of which appears at 10, and is provided with a central aperture 11 in which is registered the upper end of an insulating air supply conduit 12. The conduit 12 is connected at its lower end (not shown) through a suitable control valve with a reservoir or other source of air (or gas) under pressure, the conduit being thereby adapted to supply air or gas under pressure to the contact chamber 3 during the circuit-interrupting operation, which air or gas pressure will displace the piston 2a and

thereby the moving contact 2 toward the right in the drawing so as to separate the contacts. The air or gas pressure within the contact chamber 3 will then result in flow of air or gas radially through the gap between the contacts and axially through the passages within the tubular contacts 1 and 2 so as to extinguish the arc in well known manner, the air or gas of the blast and the arc gases being discharged to atmosphere from the outer ends of said contacts. If desired suitable means indicated diagrammatically at 13 and 14 may be provided for cooling said gases in otherwise known manner.

The cover plate 7 is secured to a flange 15 provided on the cylinder 6 by means of bolts 16 whereby said cover plate may readily be removed from the cylinder so as to allow withdrawal of the contact construction 8, spring 9, piston 2a and contact 2 from the arcing chamber when inspection of, or attention to, the contacts is required, this withdrawal of the contact being facilitated by the arrangement in which the air supply conduit 12 is disposed perpendicularly to the direction in which said contact is withdrawn from the contact chamber. It will be seen that when the parts above referred to have been withdrawn from the cylinder 6 access may readily be obtained through the cylinder 6 to the contact face of the fixed contact 1.

It will be understood that the unit shown in Fig. 1 may be arranged in any desired manner in a switch or circuit breaker. One example is shown in Fig. 2, this circuit breaker comprising a double-break switch consisting of two units A and B each constructed in accordance with Fig. 1 and mounted on a suitable foundation 26 by means of the tubular insulating pillars designated 10 in Fig. 1 and designated 10A and 10B respectively in Fig. 2. The contact chambers 3 of the two units are mounted on the pillars 10A and 10B so that the two insulating bushings 4 extend outwardly away from one another whilst the contact chambers of the two units carry fixed contacts 21A and 21B adapted to be connected together by a movable bridging bar 22 which is fixedly mounted at its centre on a rotatable insulating pillar 23 mounted on the foundation 26 in a rotatable manner and adapted to be rotated about its vertical axis by suitable operating means as part of the circuit-breaking operation. In the illustrated position of the bar 22 the latter engages at its two ends with the contacts 21A and 21B respectively. The two conductors 33 and 34 to be connected by the switch are connected with the end plates 1b of the units A and B, respectively, so that the circuit will proceed in series through two pairs of circuit-interrupting contacts, that is to say through the units A and B, and the bridging bar 22. The operating mechanism for the bridging bar 22 is arranged as is otherwise well known in the art so that movement of said bar is co-ordinated with the application of air or gas pressure to the contact chambers 3 to provide isolation by disengagement of said bar from the contacts 21A and 21B as part of the circuit-opening operation either simultaneously with or after the separation of the arc interrupting contacts 1 and 2 in each of the units A and B and extinction of the arc between said contacts whereby, upon removal of the air or gas pressure from said unit and consequent reclosure of the arc interrupting contacts 1 and 2, the circuit will remain interrupted by the bridging bar 22.

Figs. 3 and 4 show, also by way of example, 75

another form of double-break switch in which, in place of the central insulating pillar 23 and bridging bar 22, the isolating movement above referred to is obtained by bodily movement of the arc interrupting units with respect to one another. For this purpose in the arrangement of Fig. 3 the contact chambers 3 are mounted on the pillars 10A and 10B so that the insulating bushings 4 extend toward one another and, in the closed position of the switch, in line with one another, and the insulating pillars 10A and 10B are arranged to be rotated in opposite directions to one another by suitable operating mechanism. The unit B is provided with a contact blade 30 carried by the plate 1b of that unit so as to be in electrical connection with the fixed contact 1 of said unit, whilst the unit A is provided with a co-operating jaw contact 31 carried by the plate 1b of the unit A and thereby in contact with the fixed contact 1 of the unit A. The two contact chambers 3 carry respective connecting members 32A and 32B mounted on the tops of the respective contact chambers 3 in a manner permitting relative rotational movement between said members and contact chambers about the vertical axis of the insulating pillars 10A and 10B respectively. These members 32A and 32B are connected with the two conductors 33 and 34.

The switch is illustrated in Figs. 3 and 4 in the circuit-closed position. The isolating movement is obtained by the rotational movement of the insulating pillars 10A and 10B and the switch units A and B to the positions indicated at A' and B' in Fig. 4, the isolating movement being obtained by separation of the contacts 30 and 31.

It will be understood that the desired isolating operation for maintaining the circuit open after reclosure of the arc-interrupting contacts within the arcing chamber or chambers in single- and multi-break switches may be obtained by any other desired arrangement such as, for example, by means of a separate air-break switch as is also otherwise well known in the art. One arrangement of this kind appears in Fig. 5, which shows, as will now be described, an alternative application of arc-interrupting contact units according to Fig. 1 to provide a multi-break switch.

In the arrangement shown in Fig. 5 two arc-interrupting contact units A and B are mounted one above the other, the contact chamber 3 of the unit A being mounted on the upper end of the insulating pillar 10 as in Fig. 1 whilst the contact chamber 3 of the unit B is mounted upon and spaced with respect to the contact chamber 3 of the unit A by means of an insulating pillar 40. The insulating bushings 4 of the two units extend in the same direction from the vertical axis of the insulating pillars 10 and 40 and with their axes conveniently in the same vertical plane as is shown in the figure. The end plate 1b of the unit A is connected by means of a conductor 41 with the contact chamber 3 of the unit B whilst the member 1b of said unit B is connected with the conductor 33. The contact chamber 3 of the unit A is connected with the other conductor 34, in general through contact means providing the isolating movement above referred to, which isolating movement is provided in the arrangement shown by way of example in Fig. 5, by means of a separate isolating switch comprising a conducting blade 42 pivotally mounted at its right-hand end upon the upper end of an insulating pillar partially shown at 43 and engaging at its left-hand end with a contact member 44 carried by the contact chamber 3 of the

unit A. This conducting blade 42 is adapted to be disengaged from the contact 44 by a clockwise movement to the position shown at 42' by operating means actuated through a rotatable insulating pillar 45, such arrangements being otherwise well known in the art.

It will be understood that further arc-interrupting contact units may be mounted above the unit B according to the number of breaks required for arc interruption in any particular application of the arrangement including those shown in Figs. 2, 3 and 4. One such modification provides a further unit C which is indicated in broken lines in Fig. 5, the additional unit C being supported on the unit B by a tubular insulator 40' with the plate 1b of the unit B connected by conductor 41' with the contact chamber 3 of said unit C and the plate 1b of said unit C connected with the conductor 33.

In another modification of the arrangement shown in Fig. 5 the several units are mounted one above the other with the insulating bushings 4 thereof extending in diametrically opposite directions to one another from the vertical axis of the arrangement, the conductor 41 extending from the member 1b of the unit A to the member 7 of the unit B and the conductor 41', in the case of a three-unit switch, extending from the member 1b of the unit B to the member 7 of the unit C.

It now will be appreciated that the above-described basic interrupting unit constructed in accordance with my invention as exemplified in Fig. 1, which includes a metallic arcing chamber comprising a main body portion from which two cylinders or sleeves extend outwardly in different directions, one cylinder for receiving an easily removable insulated contact element and the other for receiving an easily removable contact element which is electrically connected to the chamber body, provides a very useful and desirable arrangement which is readily adaptable for a variety of different applications; for it will be apparent that whereas one connection of the circuit through the unit must be made at the terminal 1b of the bushing 4, the other connection may be tapped off from any appropriate point at the metal casing 3 which is most convenient for the particular application in view.

In the above-described examples, it will be clear that three such convenient optional tap-off points from the chamber 3 were employed. There were, firstly, either the member 7 or 14 of Fig. 1 in the case of the arrangements illustrated by Fig. 2 and the unit A of Fig. 5; secondly, the cover 48 of Fig. 1 in the embodiment shown by Fig. 3; and thirdly, the clamping member 4a of Fig. 1 in the case of units B and C depicted in Fig. 5.

Furthermore, the all-metal construction of the chamber 3 provides a strong fluid pressure confining casing in which the arc is drawn and blasted and which chamber moreover constitutes a mechanically strong rigid structure for mounting upon its hollow insulating pedestal and upon which may readily be stacked additional series interrupting units of similar configuration as clearly shown by Fig. 5. In all these various embodiments, it will be observed that the breaking of the one joint at flange 15 of cylinder 6 for the contact 2 is all that is necessary in order to inspect the condition of the contacts or for the removal of the retracting contact element for repair or replacement; moreover, these operations are possible without having to disturb any line terminals in the process.

Reverting to Fig. 1, it will be seen that the upper wall of the contact chamber 3 is provided with an opening 47 which as shown in Fig. 1 and in the arrangements shown in Figs. 2, 3 and 4, is closed by a cover member 48. In the application of the units of Fig. 1 to the arrangement shown in Fig. 5, or similarly for other arrangements of multi-break switch comprising two or more units stacked one above the other, the cover plate 48 is omitted from the unit A so that the tubular insulating pillar 40 will register with the opening 47 in said unit whereby the air or gas under pressure will also be delivered from the conduit 12 to the unit B and any further units mounted above the unit B, the insulating bushings such as 40 housing, if desired, an insulating conduit corresponding with that shown at 12 in Fig. 1. The separation of adjacent units in the same vertical column such as the separation provided by the insulating pillars 40 and 40' may be graded so as to obtain uniform distribution of voltage between the several pairs of arc-interrupting contacts.

Fig. 6 shows an arrangement comprising a plurality of arc-interrupting contact units in accordance with Fig. 5 and incorporating a further feature of the invention hereinbefore referred to whereby the several units are maintained in the required position with respect to one another with the insulating pillars operating under compressive stress only. Each of the contact chambers is provided on its lower external face with a circumferential flange 50 surrounding the opening at 11, this flange registering with a bore of the insulating pillar 10 in the case of the unit A and with the bore of the insulating pillar 40 in the case of the unit B. The assembly of insulating pillars and contact chamber units is shown mounted upon the upper wall, partially shown at 51, of an air storage tank or other foundation member, said wall being provided with an opening on which is seated a ring member 52 against which abuts the lower end face of the pillar 10.

In the case of the unit A the cover member 48 (Fig. 1) is replaced by an annular spacer member 53 having a flange 54 seating on the upper external face of the contact chamber 3 of said unit, this spacer member 53 registering within the opening 47 (Fig. 1) of said contact chamber and within the bore of the insulating pillar 40. The insulating tube 12 extends from the tank 51 through the opening 11 in the lower wall of the contact chamber 3 of the unit A, the spacer member 53, the opening 11 in the lower wall of the contact chamber 3 of the unit B and through the opening 47 (Fig. 1) in the upper wall of the last-mentioned contact chamber, said insulating tube 12 being provided with openings at 55 and 56 through which openings the pairs of contacts 1, 2 of the two units A and B respectively extend. At its lower end the tube 12 has secured thereto a metal sleeve 57 which registers within the bore of the member 52 and of the insulating pillar 10 and which is provided with a flange 58 abutting against the end surface of the member 52. An air supply conduit is partially shown at 59 making a flanged joint with the flange 58, this conduit being connected with a control valve whereby the air pressure within the tank 51 may be supplied to the tube 12. At its upper end the tube 12 has secured thereto a metal end closure member 60 which registers within the opening 47 in the unit B and 75 is externally screw-threaded to receive a ring

nut 61 abutting against the upper external face of the contact chamber 3 of said unit B.

It will be seen that tightening of the ring nut 61 against the upper face of the chamber 3 of the unit B will place the insulating tube 12 in tension against the abutment of the flange 58 on the member 52, whereby the insulating pillars 10 and 12 are placed in compression so that whereas said outer insulating members 10 and 12 may be formed of porcelain or other ceramic material not well adapted for operation in tension, the internal pillar 12 may be formed of material having desirable properties for operation in tension, for example said inner tube may be formed of vulcanite or Bakelite paper. It will furthermore be seen that the arrangement is such that all the parts are retained in coaxial relation to one another by the flanges 59 and the members 53, 57 and 60.

If desired capacitance or other grading means may be provided for effecting a uniform, or other desired grading of, distribution of potential between the several pairs of co-operating contacts of the switch such as to obtain a uniform distribution of potential between the several breaks and according to a further feature of the invention said means are obtained by suitable proportioning of the capacitance of the tubular members between the adjacent contact arrangements. For this purpose said tubular members may be provided therein with layers of conductive material in the same manner as a condenser bushing or the members may be formed of a material having a suitably high specific inductive capacity such as, for example, the material sold under the registered trade-mark Rutile.

Fig. 7 shows a modified arrangement of two contact chamber units according to Fig. 1 to form a double-break switch. In the arrangement shown in Fig. 7, the upper unit B instead of being mounted upon the lower member A by means of an insulating pillar as in Fig. 5, is mounted directly thereon so as to be in electrical connection therewith. The insulating bushings 4 of the two units extends in diametrically opposite directions from the vertical axis of the arrangement and the conductors 33 and 34 to be controlled by the switch are connected on the one hand with the member 1b of the unit B and on the other hand with the corresponding member 1b of the unit A. The unit A is shown by way of example as carrying on the plate 1b thereof a fixed contact 48 co-operating with a pivoted blade 42 corresponding with the arrangement of isolator switch shown in Fig. 5.

The arrangement of the contact chambers 3 may be identical with that shown in Fig. 1 except that the two units are connected together by mating flanges 65 and 66 formed respectively on the upper face of the unit A and the lower face of the unit B.

It will be appreciated that with the arrangement shown in Fig. 7 additional units may be mounted above the unit B so as to be connected in series therewith and furthermore, if desired, in place of the two or more separate units, the several contact chambers may be formed integrally with one another by a single metal construction, that is to say in effect the insulating bushings 4 and cylinders 6 for all the units may be mounted in a common contact chamber.

Fig. 8 shows a modification of the contact unit of Fig. 1, and applicable in the various applications of the units as described with reference to Figs. 2 to 7 inclusive, in which, instead of the

movable contact 2 being mounted in conductive relation with the arcing chamber, said contact 2 is insulated from said chamber. Thus, in Fig. 8 the moving contact 2 and piston 2a together with the resilient annular contact 8 are mounted within a cylindrical member 70 which is received within the bore of a second insulating bushing 71 secured within a suitable cylindrical portion 72 of the contact chamber 3, replacing the cylinder 6 and identical with that at 5 which, as shown in Figs. 1 and 8, locates the insulating bushing 4. In the arrangement shown in Fig. 8 the cylindrical member 70 is provided with a portion 73 of reduced diameter providing a flange against which the annular contact 8 abuts to provide reaction for the compression spring 9 and providing a continuance of the discharge passage through the contact 2 but somewhat larger than the cross-sectional area of that within said contact 2. The cylindrical bushing assembly 70, 71 is united concentrically by means of a flange 74 abutting against the inner end of the bushing 71 and by means of the end plate 6 having screw-threaded relation to the portion 73 and abutting against the outer end face of the bushing 71.

The bushing 71 is retained in place within the cylindrical portion 72 of the arcing chamber by means of an annular retaining ring 75 whereby the bushing 71, complete with the movable contact, may readily be removed from the arcing chamber when inspection and replacement of the contacts is required.

It will be understood that if desired in the arrangements shown in Figs. 1 and 8 access to the contacts for inspection of or attention to the latter, or at least of and to the contact 1, may be gained by removal of the bushing 4 from the arcing chamber, since the bushing is located in place by means of the removable annular retaining ring 4a secured to the contact chamber by means of the bolts shown. In the case of Fig. 1 however, inspection of and attention to the contact 1 through the cylinder 6 after removal of the moving contact and associated parts will normally be more convenient so that breaking of the joint between the bushing 4 and the arcing chamber is thereby obviated.

It will be understood that where desired both of the contacts 1 and 2 may be provided with a piston such as the piston 2a described with reference to the contact 2 and working within co-operating cylinders, whereby both the contacts are adapted to be displaced by the air or gas pressure to effect the arc extinguishing contact separation. For example, in the arrangements of both Figs. 1 and 8, the contact 1 and bushing 4 may be arranged similarly to the contact 2 and bushing 71 of Fig. 8.

It will be seen that the arrangements according to the invention possess the further advantage, for both single- and multi-break switches, of requiring insulating members of only a comparatively small diameter.

Having shown and described several embodiments of an improved gas blast interrupter unit in which the interrupting contacts are arranged to separate outwardly in a direction substantially perpendicular to said unit's hollow fluid conducting and supporting insulating structure, which unit is economical to manufacture, easy to assemble, readily accessible and adaptable for various practical applications; it should be understood that my invention is not limited to specific details of construction and arrangements here-

in illustrated, and that changes and modifications may occur to one skilled in the art, without departing from the spirit of my invention.

What I claim as new and desire to secure by Letters Patent of the United States is:

1. An electric circuit breaker of the gas blast type comprising an arcing chamber formed of metal, a plurality of relatively movable contacts associated with said chamber and arranged to draw an arc in said chamber upon relative separation thereof, hollow insulating structure for supporting said arcing chamber, means for supplying gas under pressure to said chamber for arc extinguishing purposes through said hollow insulating structure, said metallic arcing chamber comprising a hollow body portion within which said contacts separate, an apertured base portion for said body adapted for mounting upon said hollow insulating structure, a first sleeve branching laterally outward from said body in one direction, a second sleeve branching laterally outward from said body in another direction, means disposed in said first sleeve for supporting one of said contacts insulatingly with respect to said metallic arcing chamber, means cooperating with said second sleeve for supporting therein another of said contacts conductively with respect to said metallic arcing chamber, and a discharge opening from said chamber for exhausting the gaseous products of said arc.

2. An electric circuit breaker of the gas blast type comprising an arcing chamber formed of metal, a plurality of relatively movable contacts associated with said chamber and arranged to draw an arc in said chamber upon relative separation thereof, hollow insulating structure for supporting said arcing chamber, means for supplying gas under pressure to said chamber for arc extinguishing purposes through said hollow insulating structure, said metallic arcing chamber comprising a hollow body portion within which said contacts separate, an apertured base portion for said body adapted for mounting upon said hollow insulating structure, a first sleeve branching laterally outward from said body in one direction, a second sleeve branching laterally outward from said body in another direction, means disposed in said first sleeve for supporting one of said contacts insulatingly with respect to said metallic arcing chamber, means cooperating with said second sleeve for supporting therein another of said contacts conductively with respect to said metallic arcing chamber, one of said contacts being hollow thereby defining a discharge opening from said chamber for exhausting the gaseous products of said arc.

3. An electric circuit breaker of the gas blast type comprising an arcing chamber formed of metal, a plurality of relatively movable contacts associated with said chamber and arranged to draw an arc in said chamber upon relative separation thereof, means including a piston and a closing spring associated with one of said contacts to define therewith a retractable contact, means for supplying gas under pressure to said chamber for causing relative separation of said contacts and extinguishment of the arc drawn therebetween, said metallic arcing chamber comprising a body portion within which said contacts separate, means for supporting one of said contacts insulatingly with respect to said body, a sleeve branching laterally outward from said body, means cooperating with said sleeve for supporting therein said retracting contact, a readily disconnectable joint for said sleeve the breaking

of which suffices for the removal of said retractable contact, and a discharge opening from said chamber for exhausting the gaseous products of said arc.

5. An electric circuit breaker of the fluid blast type comprising a structure defining an arc extinguishing chamber, a pair of relatively separable contacts arranged to draw an arc in said chamber, a fluid motor for causing relative separation of said contacts, means for supplying fluid under pressure to said chamber to operate said fluid motor and to provide an arc extinguishing medium adjacent said contacts, said arc extinguishing chamber comprising a hollow metallic body portion within which said contacts separate, an apertured base portion for said body adapted for mounting on a hollow insulating supporting structure through which said fluid is supplied, a sleeve extending laterally outward in one direction from said body for supporting one of said contacts and said fluid motor, an electric bushing extending laterally outward from said body in another direction for supporting the other said contact insulatingly with respect to said body, a readily disconnectable joint for said sleeve the breaking thereof sufficing for the removal of said fluid motor and providing direct access to said contacts, one of said contacts being hollow thereby defining a discharge opening from said chamber for exhausting the gaseous products of said arc.
10. 5. A multi-break electric circuit breaker comprising a plurality of identical arcing chambers each having a pair of relatively movable contacts associated therewith, each of said arcing chambers including a hollow metallic body within which said contacts separate to draw an arc, a first opening in one end of said body, a second opening in the opposite end of said body in axial alignment with said first opening, means associated with said first opening to provide an interlocking male portion for matching with said second opening, means for stacking said arcing chambers one above the other in a column whereby adjacent chambers interlock together with all said openings in axial alignment so that said chambers communicate with each other, means for supplying fluid under pressure to one of said chambers and consequently to all of said chambers through said aligned openings, and means for causing relative separation of all said pairs of relatively movable contacts in response to the supplying of fluid under pressure to said chambers.
15. 6. A multi-break electric circuit breaker comprising a plurality of identical arcing chambers each having a pair of relatively movable contacts associated therewith, each of said arcing chambers including a hollow metallic body within which said contacts separate to draw an arc, a first opening in one end of said body, a second opening in the opposite end of said body in axial alignment with said first opening, means associated with said first opening to provide an interlocking male portion for matching with said second opening, means for stacking said arcing chambers one above the other in a column including a tubular insulator interposed between each adjacent pair of chambers, means associated with each said insulator to provide an interlocking male portion at one end and a bore at the opposite end similar to the first and second openings respectively in each said arcing chamber whereby all said stacked chambers and insulators interlock progressively with holes and
20. 70.

bore in axial alignment, means for supplying fluid under pressure to one of said chambers and consequently to all of said chambers through said aligned openings, means for causing relative separation of all said pairs of relatively movable contacts in response to the supplying of fluid under pressure to said chambers, and means for connecting said pairs of contacts in series relationship.

7. A multi-break electric circuit breaker comprising a plurality of identical arcing chambers each having a pair of relatively movable contacts associated therewith, means for stacking said arcing chambers one above the other in a column, the adjacent walls of any two adjacent chambers being provided with aligned openings so that said chambers communicate with each other, a tubular member of insulating material extending through said aligned openings from end to end of said column, means for supplying fluid under pressure to one of said chambers and consequently to all of said chambers through said tubular member, and means for causing relative separation of all said pairs of relatively movable contacts in response to the supplying of fluid under pressure to said chambers.

8. A multi-break electric circuit breaker comprising a plurality of identical arcing chambers each having a pair of relatively movable contacts associated therewith, means for stacking said arcing chambers one above the other in a column, the adjacent walls of any two adjacent chambers being provided with aligned openings so that said chambers communicate with each other, a tubular member of insulating material extending through said aligned openings from end to end of said column, an insulating tube between each of said chambers, means for placing said tubular member in tension and consequently said insulating tubes in compression, means for supplying fluid under pressure to one of said chambers and consequently to all of said chambers

bers through said tubular member, and means for causing relative separation of all said pairs of relatively movable contacts in response to the supplying of fluid under pressure to said chambers.

9. A multi-break electric circuit breaker comprising a plurality of identical arcing chambers each having a pair of relatively movable contacts associated therewith, means for stacking said arcing chambers one above the other in a column, the adjacent walls of any two adjacent chambers being provided with aligned openings so that said chambers communicate with each other, a tubular member of insulating material extending through said aligned openings from end to end of said columns, an insulating tube between each of said chambers, means for placing said tubular member in tension and consequently said insulating tubes in compression, means for supplying fluid under pressure to one of said chambers and consequently to all of said chambers through said tubular member, means for causing relative separation of all said pairs of relatively movable contacts in response to the supplying of fluid under pressure to said chambers, and means for connecting said pairs of contacts in series relationship.

CEDRIC HAROLD FLURSCHEIM.
